UNITED STATES PATENT OFFICE.

WILLIAM MARSHALL, OF DETROIT, MICHIGAN, ASSIGNOR TO BRIGGS MANUFACTURING COMPANY, OF DETROIT, MICHIGAN, A CORPORATION OF MICHIGAN.

ADJUSTABLE STRIKER PLATE.

Application filed February 21, 1927. Serial No. 169,980.

This invention relates generally to adjustable striker plates designed for use in connection with the latch bolts of vehicle doors and consists of certain novel features of construction, combinations and arrangements of parts as will be more fully described and particularly pointed out in the appended claims.

In the accompanying drawing:

10 Figure 1 is a fragmentary elevation of a door jamb with a striker plate embodying my invention applied thereto.

Figure 2 is a perspective view of the striker plate and retainer plate therefor;

15 Figure 3 is a sectional view taken on the line 3—3 of Figure 1.

Figure 4 is a detail plan view of the retainer plate.

Referring now to the drawing, 1 is a 20 striker plate, and 2 is a retainer plate therefor of an assembly embodying my invention. As shown, the striker plate 1 is formed from a single sheet of metal and has an elongated flat base portion 3, a relatively short inclined portion 4, and a pair of lateral projections 5 and 6 respectively. Preferably the lateral projections 5 and 6 are located at the ends of the striker plate, while the inclined portion 4 is between the base 3 and the innermost projection 6. The outer projection 5 inclines outwardly with respect to the base 3 and has a return-bent portion 7 that terminates in substantial alignment with but in spaced relation to the base portion 3, while the inner projection 6 extends outwardly from the inner end of the inclined portion 4 at substantially right angles to the base 3 and has a return-bent portion 8 that terminates adjacent to the inner edge 40 of the inclined portion 4.

The retainer plate 2 is also formed from a single sheet of metal and has a substantially U-shaped body portion 9, laterally extending attaching portions 10 and 11, and inwardly extending stiffening flanges 12 and 13. As shown, the base 14 of the body portion 9 is provided adjacent to its inner end with an inclined portion 15 that corresponds to and serves as a bearing for the inclined portion 4 of the striker plate, and is provided at its outer end with an outwardly projecting flange 16 that is disposed at substantially right angles to the base 14 and terminates in an outwardly projecting rounded flange 17. The 55 attaching portions 10 and 11 are disposed in

a common plane and have openings 18 and 19 respectively for receiving suitable securing elements.

In the present instance the retainer plate 2 is secured to the base 20 of a channel-shaped door jamb. As shown, the base 20 of this jamb has an elongated opening 21 for receiving the latch bolt 22 of the door, and the attaching portions 10 and 11 are secured to the inner face of the base 20 above and below said opening 21 so that the rounded flange 17 overlaps the adjacent outer wall 23 of the jamb. The striker plate 1 is preferably adjustable transversely of the retainer plate 2 toward and away from the flange 16 and is adapted to be held in adjusted position by suitable screws 24 and 25 respectively. Preferably the screw 24 extends through an elongated slot 26 in the flat base portion 3 and threadedly engages the opening 27 in the base portion 14, while the screw 25 extends freely through an elongated slot 28 in the inclined portion 4 and threadedly engages an opening 29 in the inclined portion 15. Thus with this construction the striker plate may be adjusted on the flat base 14 without interfering with the usual trimming material of the vehicle body for taking up wear and preventing rattling, and may be easily and quickly maintained in such adjusted position. It will also be noted that the flat base portion 14 serves as a bearing for the flanges 7 and 8 respectively so that the striker plate is braced and thereby materially reinforced in any adjusted position. In use, the rounded projection 17 serves as a fixed step for the latch bolt for maintaining the door in partially closed position, while the projection 5 constitutes a second step arranged in tandem with the first step for maintaining the door in fully closed position. Due to this arrangement the assembly is simple in construction and can be manufactured at a comparatively low cost.

While it is believed that from the foregoing description, the nature and advantage of my invention will be readily apparent, I desire to have it understood that I do not limit myself to what is herein shown and described and that such changes may be resorted to when desired as fall within the scope of what is claimed.

What I claim as my invention is:

1. A striker plate comprising a sheet metal

stamping having a substantially flat base portion, and laterally projecting portions at the ends of said base, one of said portions having an inclined face serving as a step for a latch bolt.

2. A striker plate having a substantially flat base portion and an inclined portion provided respectively with elongated slots for securing elements, and a lateral projection at one end of one of said portions constituting a step for a latch bolt.

3. A striker plate having a substantially flat base and an inclined portion provided respectively with openings for securing elements, a lateral projection at one end of the base constituting a step for a latch bolt, and a lateral projection at an end of said inclined portion having a return-bent portion reinforcing and bracing the plate.

4. A striker plate having a substantially flat base and lateral projections rigid with and arranged in tandem on the base, both of said projections having return-bent portions reinforcing and bracing said plate, one of said projections constituting a step for a latch bolt.

5. A retainer plate for striker plates and the like having a channel-shaped portion provided at the sides of the channel with attaching flanges and provided at one end of the base of the channel with a lateral projection constituting a step for a latch bolt.

6. A retainer for striker plates and the like having longitudinally spaced substantially flat attaching portions and an intermediate substantially channel-shaped portion for receiving an adjustable step for a latch bolt and provided at one end of the base of said channel portion with a lateral projection constituting a fixed step for a latch bolt.

7. In combination, a striker plate having a substantially flat base provided with a lateral projection constituting a step for a latch bolt, and a retainer plate for said striker plate having a substantially flat bearing portion for said base aforesaid and having a lateral projection arranged in tandem with the lateral projection aforesaid and constituting a fixed step for a latch bolt.

8. In combination, a striker plate having a substantially flat base, an inclined portion, and a lateral projection at an end of one of said portions constituting a step for a latch bolt, said base and inclined portions being provided respectively with elongated slots for receiving securing elements, and a re-

tainer plate having substantially flat attaching portions, and an intermediate substantially channel-shaped portion receiving said striker plate, the base of said channel portion having a flat portion and an inclined portion constituting seats respectively for the base and inclined portions of said striker plate, the flat and inclined portions of the base of said channel portion having threaded openings for securing elements, and securing elements extending freely through said slots and threadedly engaging said openings for maintaining said striker plate in position upon said retainer plate.

9. A striker plate having a substantially flat base portion, and an inclined portion, said inclined portion being provided with a lateral projection, said projection having a return bent portion extending slightly beyond the upper edge of said inclined portion and terminating adjacent to said flat base portion.

10. A striker plate having a substantially flat base portion provided with a lateral projection constituting a step for a latch bolt, said projection having a return bent portion terminating in substantial alignment with but in spaced relation to said base portion, and constituting a brace for said step.

11. In combination, a retainer plate having spaced serrated portions, and a striker plate adjustably mounted on said retainer plate and having lateral projections, one of said projections having a face serving as a step for a latch bolt and both of said projections having return bent portions terminating adjacent to said base and engageable with said spaced serrations, and means for maintaining said projections in engagement with said serrations for detachably holding said striker plate in adjusted position.

12. In combination, a jamb having a recess at an edge thereof, a retainer plate having a substantially U-shaped body fixed in said recess, a flange projecting from the base of the U in the direction of the flanges of the U, and having a rounded extension projecting forwardly and overlapping an edge of the recess in the jamb and constituting a fixed step for a latch bolt, and a striker plate adjustably mounted in said U-shaped body in rear of the flange aforesaid and having a lateral projection in tandem with the extension aforesaid and constituting a second step for a latch bolt.

In testimony whereof I affix my signature.
WILLIAM MARSHALL.
